[57] CLAIM

The ornamental design for a spinner fishing lure, as shown and described.

DESCRIPTION

FIG. 1 is a top plan view of a spinner fishing lure, showing my new design, the bottom being a mirror image thereof;

FIG. 2 is a left side elevational view, the right side being a mirror image thereof;

FIG. 3 is a front elevational view thereof; and,

FIG. 4 is a rear elevational view thereof.

FIG. 1

FIG. 2

FIG. 3

FIG. 4
